UNITED STATES PATENT OFFICE.

EDMUND GARSIDE, OF DARLINGTON, ENGLAND, ASSIGNOR TO JOHN HENRY MORGAN, OF SHEFFIELD, ENGLAND, AND TO THE SKERNE WORKS LIMITED, OF DARLINGTON, ENGLAND, A CORPORATION OF GREAT BRITAIN AND IRELAND, AND HIMSELF.

DIVIDED DRIVING PULLEY AND THE LIKE OF SHEET-METAL CONSTRUCTION.

Application filed October 22, 1920. Serial No. 418,818.

To all whom it may concern:

Be it known that I, EDMUND GARSIDE, subject of the King of Great Britain and Ireland, residing at Skerne Works, Darlington, in the county of Durham, England, have invented new and useful Improvements in and Relating to Divided Driving Pulleys and the like of Sheet-Metal Construction, of which the following is a specification.

10 This invention relates to improvements in divided driving pulleys and the like of sheet metal construction and has for its object the provision of means whereby great strength, light weight and low prime cost are obtained.

15 The invention consists in the formation of the whole of the arms of one half of a pulley or the like from a single sheet of metal, a half bush for association with said arms, sheet metal means involving lugs for clamping bolts attached to said half bush and means for attaching the sheet metal means to the arms element in conjunction with a half rim element and means for attaching the outer ends of the arms thereto.

25 In the drawings,

Fig. 1 illustrates a blank with stiffening ribs, suitable for forming into a three armed element, after the first shearing operation.

Fig. 2 illustrates the same blank as shown in Fig. 1 after the bending operation.

Fig. 3 is a side elevation of Fig. 2.

Fig. 4 illustrates a three armed element after the arms have been fan spanned.

Fig. 5 illustrates a half bush in perspective.

Figs. 6, 7, 8, 9, and 10 illustrate the various steps for producing the elements for the boss.

Fig. 11 is a front elevation of the stiffening plate.

Fig. 12 is a side elevation of Fig. 11.

Fig. 13 is a perspective view of a complete pulley constructed in accordance with this invention and Fig. 14 is a section through the rim edge drawn to an enlarged scale.

The construction of one half of a driving pulley having six arms will first be described but it is obvious that many modifications thereof may be made without departing from the spirit of the invention.

A sheet of metal of suitable length and width has four slots or notches a formed therein as illustrated in Fig. 1, the longitudinal axis a' of the slots a being parallel

with the longitudinal axes a^2 a^2 of the sheet, 55 two of the slots a extend from one end of the sheet and two from the other for a distance a^3 substantially equal to the length of the finished arms A. To stiffen the arms A, raised ribs or ridges a^4 may be used and 60 when such are employed the raising thereof is effected prior to the formation of the slots a .

The sheet of metal is now folded substantially into U shape as illustrated in Figs. 2 65 and 3, the upstanding parts of the U involving the portions with the slots or notches a and the transverse joining part a^5 being disposed substantially at right angles thereto.

The transverse joining part a^5 is then curved 70 as illustrated in Fig. 4 to fit the external diameter of a suitable half bush, B (Fig. 5) said curving resulting in the divergence of the parts separated by the slots or notches a thereby producing three substantially radial arms A, see Fig. 4. On each side of the element comprising the arms A a segmental plate C, Figs. 11 and 12, is attached by

75 rivets a^7 , which pass through the holes c' in the plate C and a^8 in the arms A, the segmental plates C having a part c^2 thereof removed to accommodate the parts of the half bush B which protrude therethrough.

Each of the segmental plates C are formed with ridges or ribs c^3 adapted to engage with the ribs a^4 of the arms A and raised portions c^4 for purposes hereinafter to be described.

To each of the segmental plates C after they are riveted in place is riveted an element D formed from sheet metal in the following manner:—

A sheet of metal of suitable thickness is first blanked out as shown in Fig. 6 and includes a hole d^1 and two notches d^2 . At 95 a single operation the edge of the hole d^1 is flanged to fit the half bush B and the ends of the projecting lugs d^3 are turned as illustrated in Figs. 7 and 8, the final step illustrated in Figs. 9 and 10 involving the

100 completion of the curling of the lugs d^3 to form bosses d^5 and the severance of the whole into two elements D D along the line d^6 .

As previously described the elements D D are riveted to the segmental plates C the rivets c^6 passing through the holes c' in the plates C and the holes d^7 in the elements D. The function of the raised portions c^4

of the plates C is now self evident and is to enable the elements D to properly bed on the plates C without interference by the ribs c^3 . The half bush B is now introduced 5 into the curved transverse joining part a^5 of the element comprising the arms A and is attached to the elements D by rivets b^2 passing through the holes b^1 in the half bush B and holes d^8 in the elements D. By this 10 arrangement of parts it will be seen that each of the arms A transmits its proper share of load to the bush B. The outer ends of the arms A associated together are attached to a half rim element E by means 15 of angle brackets e^1 to which both the half rim E and the arms A are riveted or alternatively the brackets e^1 may be formed from the material of which the arms A are made.

In order to stiffen the half rim elements 20 E and enable material of comparatively light gauge to be employed the edges of the elements E are rolled as shown in Figs. 13 and 14 at e^2 the abutting part e^3 of said roll being disposed normal to the driving 25 surface so as to obtain a maximum of support.

To produce a complete pulley as illustrated in Fig. 14, two halves constructed as hereinbefore described are connected by 30 bolts F which pass through the bosses d^5 , and plates e^4 which are riveted to one end

of each half rim element E at e^5 and are provided with holes which register with holes in the end of the element E abutting and adapted to receive bolts e^6 .

35

I claim:

1. In a divided driving pulley of sheet metal construction in which the whole of the arms of one half thereof are formed from a single sheet of metal, the arrangement of a 40 half bush formed of sheet metal and adapted to engage both the shaft and one of the arm elements, segmental plates riveted to the arms and boss elements of sheet metal riveted to said segmental plates and said half 45 bush.

2. In a divided driving pulley as claimed in claim 1, the formation of a boss element from a blank having two pairs of oppositely disposed lugs and an elongated hole, the 50 said hole being flanged and the said lugs being curled to form bosses, the element thus formed being divided to form two similar parts.

In testimony whereof I have signed my 55 name to this specification in the presence of two subscribing witnesses.

EDMUND GARSIDE.

Witnesses:

JOHN WILLIAM SHAW,
ARTHUR EDWIN HENRY SMITH.
